UNITED STATES PATENT OFFICE.

WILLIAM E. CO HAGAN, OF DENVER, COLORADO.

PISTON RING.

Application filed April 23, 1923. Serial No. 633,913.

To all whom it may concern:

Be it known that I, WILLIAM E. CO HAGAN, a citizen of the United States, residing at Denver, the city and county of Denver and State of Colorado, have invented certain new and useful Improvements in Piston Rings; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to piston rings of the type disclosed and claimed in Patent No. 1,385,508, granted to Lou J. Trembley on the 26th day of July, 1921.

It is the object of this invention to obtain a better and more perfect seal between the piston ring and the piston than can be obtained by the arrangement shown and claimed in the patent referred to.

I have found that in order to obtain the best possible sealing action between the ring and the piston, it is necessary to make the inner surface of the ring in the shape of a W and to make the width of the ring slightly less than the width of the slot in the piston so that the ring has a slight longitudinal movement on the piston as the latter reverses its direction of travel. The cork seal is formed into such a cross-sectional shape that it fits into the channels in the W-shaped inner surface of the ring and is slightly wider than the ring groove so as to be slightly compressed when it is put into the same. The cork will therefore remain stationary and the ring will be permitted to move slightly, which results in a double seal in both directions of travel of the piston in a manner which will hereinafter be described, reference being had for this purpose to the accompanying drawing in which my improved ring has been illustrated, and in which:

Fig. 1 is a side elevation of a piston showing the rings in place thereon.

Fig. 2 is a top plan view of the piston looking in the direction of the arrow 2 in Fig. 1.

Fig. 3 shows the relative location of the parts when the piston travels downwardly; and

Fig. 4 shows the relative location of the parts during the up-stroke of the piston.

The same reference numbers will be used to designate the same parts throughout the several views.

The numeral 5 represents a piston which is provided with a number of grooves 6 for the reception of piston rings. In the bottom of each groove there is a cork packing 7 which is preferably treated and formed into the desired shape in accordance with the method described and claimed by me in my Patent No. 1,439,869, granted to me on the 26th day of December, 1922. The cork packing 7 is first made into strips which have one flat side which fits against the bottom of the groove and the other side made with two parallel longitudinal projections 8 which cooperate with the grooves in the inner surface of the ring 9 in the manner shown in Figs. 3 and 4 of the drawing. The rings 9 differ from the ordinary piston ring in this, that the inner surface has two V-shaped grooves extending parallel with the edges of the ring. These grooves are so cut that the central rib 10 is nearer to the outer surface of the ring than the outer edges 11. This makes the inner side have the shape of a capital W. The inclined sides of the inner surface of the ring cooperate with the correspondingly inclined sides of the cork packing. As has been already pointed out above, the ring 9 is slightly narrower than the slot and therefore when the piston moves downwardly, as indicated by the arrow in Fig. 3 the friction between the ring and the sides of the cylinder will cause the ring to move upwardly relative to the piston, until it contacts with the upper side of the groove. This will cause the sides of the W, which are designated by numerals 12 and 13, to contact with the corresponding cooperating sides of the cork gasket to form a double seal. When the piston moves upwardly in the direction indicated by the arrow in Fig. 4, the friction between the cylinder and the ring will cause the latter to move downwardly relative to the piston until it comes into contact with the lower side of the groove. Sides marked 14 and 15 will now contact with the corresponding sides of the cork packing, all

as shown in Fig. 4. It will therefore appear that sides 12, 13 and 14, 15 alternately form the seals which it will be noted are double.

If the ring 9 were as wide as the groove, there could be no endwise movement and therefore when the cork gasket shrinks slightly, as it will after some time, the seal 5 would not be as perfect as it should be, while if the ring is narrower, it permits the slight movement referred to above which causes a perfect double seal, even if the gasket surface and the inner surface of the ring would 10 not do so if the ring were stationary. The arrangement of the ring, piston and packing described above, prevents oil from being "pumped" into the combustion chamber and stops the fouling of the spark plugs. It 15 also prevents gas from passing down into the crank case which would cause the oil to become thinned. The power of the engine is increased because there is substantially no compression loss and this naturally decreases 20 the consumption of gasoline.

Having now described my invention, what I claim as new is:

1. A piston packing composed of an outer expansion metallic ring and an inner layer 25 of cork, the inner surface of the piston ring having a central ridge adapted to penetrate the cork and an inwardly projecting ridge on each side of said central ridge.

2. A piston ring whose cross-section is 30 such that the outer curved surface and the sides are formed by straight lines forming three sides of a rectangle, the fourth side of which is formed by four short sides arranged at an angle with each other and with 35 the sides so as to form three inwardly projecting ridges.

3. In combination a piston having piston 40 ring grooves, a piston ring in each groove, a cork packing ring in the bottom of the 45 groove, the adjacent surfaces of the ring and packing being formed by four annular surfaces angularly related to each other.

4. In combination a piston having piston 50 ring grooves, a piston ring in each groove, a cork packing ring in the bottom of the 55 groove, the adjacent surfaces of the ring and packing being formed by four annular surfaces angularly related to each other in such a manner that an inwardly projecting ridge is formed on the ring midway between the 60 sides.

5. In combination a piston having piston 65 ring grooves, a piston ring in each groove, a cork packing ring in the bottom of the 70 groove, the adjacent surfaces of the ring and packing being formed by four annular surfaces angularly related to each other in such a manner that an inwardly projecting ridge is formed on the ring midway between the 75 sides, the sides of said ring extending inwardly beyond the central ridge.

6. In combination, a piston having piston 80 ring grooves, a piston ring in each groove, said rings being of slightly less width than the grooves so as to permit a slight transverse movement of the ring in the groove, a cork packing ring in the bottom of each groove, said packing ring being of the same width as the groove so that it will remain 85 stationary with respect to the groove, the adjacent surfaces of the piston ring and the packing ring being formed by four annular surfaces angularly related to each other in such a manner that an inwardly projecting ridge is formed on the piston ring midway between the sides.

In testimony whereof I affix my signature.

WILLIAM E. CO HAGAN.
